UNITED STATES PATENT OFFICE.

GEORGE LUTZ, OF CAMBRIDGE, MASSACHUSETTS.

PIANO.

1,331,572.

Specification of Letters Patent. Patented Feb. 24, 1920.

Application filed February 28, 1919. Serial No. 279,730.

To all whom it may concern:

Be it known that I, GEORGE LUTZ, a citizen of the United States, residing at Cambridge, county of Middlesex, State of Massachusetts, 5 have invented an Improvement in Pianos, of which the following description, in connection with the accompanying drawing, is a specification, like characters on the drawing representing like parts.

10 This invention relates to pianos and has for its object to provide a novel device by which the tension of the sounding board may be regulated whereby a tone of increased fullness and richness will be produced.

15 My improved device may be used in connection with either upright pianos or grand pianos, and it comprises two seat members adapted to be attached to the piano frame, a 20 bridge member adapted to rest against the seat members, and an adjusting screw carried by the bridge member and adapted to transmit pressure to the sounding board, thereby to increase the tension of the latter.

25 In order to give an understanding of my invention, I have shown it in the drawings as it might be applied to an upright piano, and I will first describe a selected embodiment thereof, after which the novel features 30 will be pointed out in the appended claims.

Figure 1 is a view showing the back framing of an upright piano with the sounding board attached thereto and illustrating my improved tension-regulating device;

35 Fig. 2 is a section on the line 2—2, Fig. 1;

Fig. 3 is an enlarged perspective view of the foot which rests against the sounding board;

40 Fig. 4 shows a different embodiment of the invention.

In the drawings the back framing of an upright piano is indicated generally at 1 and it comprises in its construction a plurality of vertically-extending posts 2 as usual 45 in upright pianos. 3 indicates the sounding board which is of usual construction and is shown as secured to the back framing by having its edges glued thereto, as shown at 4. Associated with the sounding board is 50 the bridge 5 against which the piano strings (not shown) rest.

The above-described parts are or may be all as usual in upright pianos and form no part of my present invention.

55 As stated above, my invention comprises a novel device adapted to be secured to the

posts 2 of the back framing and constructed to act against the rear face of the sounding board 3 thereby to force the rear face outwardly so as to produce in the sounding board the desired tension. The device herein shown for accomplishing this comprises two seat members 6 which are constructed to be secured to two adjacent posts 2, and each of which is provided with a seat portion 7 that extends laterally from the post, a bridge member 8 adapted to rest against the seat portion 7, and an adjusting screw 9 screw-threaded through the bridge member 8 and constructed to apply pressure to the 70 back side of the sounding board.

The seat members 6 are each shown as having a body portion which rests against the inside face of the post 2, and a laterally-extending flange portion 10 arranged to rest 75 against the front face of the post, each seat member being secured to the post by means of a suitable screw 11. When the two seat members are thus secured to the posts, the seat portions 7 thereof face each other and 80 form rests or seats to receive the ends of the bridge member 8.

In order to prevent the adjusting screw 9 from injuring the sounding board I propose to interpose a foot member between the 85 adjusting screw and the sounding board. This foot member is illustrated in Fig. 3 and it will preferably be formed with a wooden facing 12 which rests against the inner face of the sounding board, and a 90 metal backing 13 which has a socket or depression 14 to receive the end of the adjusting screw 9. The backing 13 is preferably placed at one end of the foot and in applying the device to a piano the seat member 6 95 is so positioned on the posts 2 that the screw will come directly back of the bridge 5 at a point about centrally of the sounding board. The foot will also preferably be arranged, as shown in Fig. 1, so that it will project 100 below the bridge and bear against the portion of the sounding board beneath the bridge.

When the device is applied to the piano, the bridge member 8 constitutes a nut for 105 the adjusting screw so that by turning the screw the central portion of the sounding board will be forced outwardly, thus placing the sounding board under increased tension. The pressure to which the screw is 110 subjected is transmitted to the posts 2 through the flanges 10 of the seat members

and thus no strain comes on the screws 11. By adjusting the screw 9 the sounding board may be given the proper tension to produce tones of the desired quality. The device is 5 very simple in construction and can be easily applied to any upright piano.

Instead of fastening the seat members 6 to two adjacent posts 2, they might both be placed on the same post, in which case the 10 bridge member would extend in a vertical rather than a horizontal direction. The 15 particular position in which the seat members are placed will depend something upon where it is desired to apply pressure to the sounding board to secure the desired results. By suitable modifications the device may also be applied to grand pianos.

I claim:

1. In a piano having the usual back framing including vertical posts and a sounding board secured thereto, the combination with 20 said posts and sounding board, of two seat members secured to two adjacent posts, a bridge member resting on said seat members, and an adjusting pin screw-threaded through the bridge member and adapted to transmit pressure to the back side of the sounding board.

2. In a piano, the combination with the 30 usual back framing including vertical posts, of a sounding board having its edges secured to said framing, two seat members secured to two adjacent posts, a bridge mem-

ber resting on said seat members, an adjusting screw screw-threaded through said 35 bridge member, and a foot interposed between the screw and the sounding board.

3. In a piano, the combination with the usual back framing including vertical posts, 40 of a sounding board having its edges secured to said framing, two seat members secured to two adjacent posts, a bridge member resting on said seat members, an adjusting screw screw-threaded through 45 said bridge member, and a foot interposed between the screw and the sounding board, said foot having a wooden face resting against the sounding board and a metal back in which the screw engages.

4. In a piano, the combination with the 50 usual back framing including vertical posts and a sounding board having its edges secured to said frame, of two seat members secured to two adjacent posts, each seat member having a body portion to overlie the 55 side of the post, a flange engaging the inner face of the post and a laterally-extending seat portion, a bridge member having its ends resting on said seat portions, an adjusting screw screw-threaded through the 60 bridge member, and a foot member interposed between the screw and the sounding board.

In testimony whereof I have signed my name to this specification.

GEORGE LUTZ.
